UNITED STATES PATENT OFFICE.

JOHN CURTIS CHEVALIER HOEHN, OF CHICAGO, ILLINOIS.

PROCESS OF HYDROGENATING UNSATURATED FATTY MATERIAL.

1,189,817.

Specification of Letters Patent.

Patented July 4, 1916.

Application filed March 13, 1914. Serial No. 824,439.

To all whom it may concern:

Be it known that I, JOHN C. C. HOEHN, a citizen of the United States, residing at Chicago, in the county of Cook and State 5 of Illinois, have invented certain new and useful Improvements in Processes of Hydrogenating Unsaturated Fatty Material, of which the following is a specification.

My invention relates to improvements in 10 processes of hydrogenating unsaturated fatty material, such as fatty acids or their glycerids, to convert the same into corresponding saturated compounds.

An important object of the invention is to 15 provide a process of the above mentioned character, whereby the hydrogen will be absorbed by the fatty material, in a quick and thorough manner, without the aid of large, expensive, or complicated apparatus.

20 In my copending application for process of and apparatus for hydrogenation of oils, Serial No. 782,491, filed August 1, 1913, I disclosed a process of hydrogenating unsaturated fatty material, which consisted 25 generally in causing fatty material, in the form of a film with a finely divided catalytic agent suspended therewith, to flow or travel over an inactive support, in the presence of an atmosphere containing hydrogen.

30 By causing the fatty material to travel in the form of a film the exposed area of the same was increased. It was not known, as far as I am aware, that hydrogen would be readily absorbed by the fatty material having 35 a finely divided catalytic agent in suspension therein when in the form of a body or mass, having a substantial depth, without the employment of violent agitation.

My prior process was also devised to eliminate violent agitation of the fatty material or oil, which is employed to increase the area of the fatty material or oil exposed to the action of the hydrogen. Violent agitation of the fatty material or oil, however, 45 possesses marked disadvantages, chief among which may be mentioned the bubbling of the hydrogen in or through the oil or fatty material. Further experiments which I have made, lead me to believe that the best

50 results are obtainable by subjecting a mass or lake of the fatty material or oil having the finely divided catalytic agent in suspension therein, and having a relatively large exposed area or surface and a substantial 55 depth, that is a depth greater than it is possible to obtain in the film, to the action of an atmosphere containing hydrogen, in the

presence of suitable heat and pressure. The fatty material or oil is held within an inactive receptacle and gently flows or is gently agitated or stirred therein, sufficiently to thoroughly mix the saturated fatty material or oil with the unsaturated material or oil contained therein. This process is based upon the well known fact that fatty material 60 or oil will absorb the hydrogen in an inverse ratio to the degree of saturation of the same by the hydrogen. Hence, if the mass or body of the fatty material has a substantial depth, say from one to three inches, and the fatty material is gently agitated, the hydrogen will be quickly and thoroughly absorbed by the fatty material or oil, the hydrogen penetrating the depth of the mass, which is aided by the stirring of the same. In my 65 improved process the same surface or area of the fatty material or oil is exposed to the action of the hydrogen, as when the same is in the form of a film, but by the mass of fatty material having a substantial depth, 70 the hydrogen continues to be absorbed more rapidly and for a much longer time.

In the accompanying drawings, forming a part of this specification and in which like numerals are employed to designate like parts throughout the same, Figure 1 is a partly diagrammatic central longitudinal sectional view through apparatus within which my process may be advantageously practised, and Fig. 2 is a similar view of a 75 slightly different form of such apparatus.

In the drawings, wherein for the purpose of illustrations is shown preferred embodiments of apparatuses for practising my process, the numeral 5 (Fig. 1) designates an outer shell, preferably horizontally arranged and provided with a removable top or cover 6. This shell is preferably air tight and capable of withstanding pressure above atmospheric pressure. Connected 80 with the cover 6 is a hydrogen inlet pipe 7, having a cut off valve 8, while a hydrogen outlet pipe 9, provided with a cut off valve 10, is connected with the outer shell 5, near the bottom thereof. Arranged within the outer shell 5, are preferably horizontally arranged oil holding pans 11, the upper portions of which are entirely open, said pans having a substantial depth, as shown. The fatty material or oil to be treated is held 85 within these pans, whereby a relatively large area or upper surface of the oil is exposed to the atmosphere containing hydrogen within the shell 5, said oil not being in the form of

a film, but in the form of a lake or mass, having a substantial depth, that is from one to three inches, which depth may of course be widely varied.

5 Means are provided to gently stir, agitate or circulate the oil within the pans 11, for the purpose of mixing the saturated portion of the oil with the unsaturated portion thereof, such stirring or agitating not 10 amounting to violent agitation whereby hydrogen bubbles will form within or through the fatty material or oil. To accomplish this, the oil is originally fed, (Fig. 1) into the lowermost pan 11 through a pipe 12, provided with a cut off valve 13. Connected with the opposite end of the lowermost pan is a pipe 14, leading into the upper portion thereof and spaced a substantial distance from the bottom of this pan. The oil within 15 the lowermost pan is withdrawn through the pipe 14, and since this pipe leads into the upper portion of the pan it is obvious that the upper or saturated portion of the oil will be removed therefrom, a predetermined depth of the oil always remaining within the pan. The pipe 14 is connected with the corresponding end of the next upper pan 11, adjacent the bottom thereof, discharging the oil therein at a point spaced 20 a substantial distance below the exposed surface of the oil contained within the intermediate pan 11. The oil is circulated upwardly through the pipe 14 by a pump 15, of any well known or preferred type, connected in the pipe 14, as shown. In a similar manner, a pipe 16 connected with the opposite end of the intermediate pan, withdraws oil from the upper portion thereof, and discharges the same into the bottom of 25 the uppermost pan 11 at a point spaced a substantial distance from the upper exposed surface of the oil. A pump 17 is connected in the pipe 16, to cause the oil to travel upwardly therein. The oil in the uppermost pan 11 discharges from the opposite end of the pan through a depending pipe 18, connected with the pan 11 near the upper portion thereof, whereby the oil is withdrawn from the upper exposed surface of the oil. 30

The pipe 18 extends downwardly and discharges the oil into one end of the lowermost pans 11, preferably below the exposed surface of the oil therein. The saturated oil may be withdrawn from each of the pans 35 through outlet means 19, preferably arranged adjacent the bottom of each pan.

The oil is preferably heated during the treatment, which may be accomplished by steam heating coils 20, preferably horizontally arranged within the main shell 5, and disposed below and adjacent the pans 11.

In the form of apparatus shown in Fig. 2, the numeral 21 designates an air tight preferably horizontal outer shell, provided with hydrogen inlet and outlet 22 and 23. Ar-

ranged preferably horizontally within the outer shell 21 in spaced superposed relation, are pans 24, identical with the pans 11. Steam heating coils 25 are employed. The saturated oil may be withdrawn from each 70 of the pans 24 through outlet means 26. The oil to be treated is fed through an upper inlet pipe 27, discharging into the upper portion of one end of the uppermost pan 24, as shown. The oil is withdrawn 75 from the opposite end of the uppermost pan through a downwardly extending pipe 28, leading into the upper portion of the uppermost pan, whereby the oil at the upper exposed surface of the mass will pass through 80 the pipe 28. This pipe is provided with a cut off valve 29. The lower end of the pipe 28 passes into one end of the intermediate pan 24, adjacent the bottom thereof, whereby oil is supplied into the pan 24 at a substantial distance from the upper exposed surface of the oil therein. Connected with the opposite end of the intermediate pan 24 is a depending pipe 30, leading into such pan adjacent its upper portion for withdrawing oil from the upper exposed surface thereof, such pipe discharging into one end of the lowermost pan 24, to feed the oil therein at a point spaced a substantial distance from the upper exposed surface of the 95 oil therein. The pipe 30 is provided with a cut off valve 31, as shown. A return pipe 32 is connected with the opposite end of the lowermost pan 24, and leads into the upper portion thereof to withdraw oil from the 100 upper exposed surface of the oil, such pipe 32 discharging the oil into one end of the uppermost pan 24, below the upper exposed surface of the oil therein. A pump 33 of any well known or preferred type, is connected in the pipe 32 and serves to cause the oil to travel upwardly through this pipe.

In the practice of my process, in connection with the form of apparatus shown in Fig. 1, the hydrogen supply being originally 110 cut off, the oil having a finely divided catalytic agent mixed therewith is fed through pipe 12 into the lowermost pan 11, and withdrawn therefrom by the pumps 15 and 17, until all of the pans are filled to a predetermined depth, at which time oil from the uppermost pan will begin to return through pipe 18 into the lowermost pan. The supply of oil is then cut off, while pumps 15 and 17 are allowed to continue to operate. 115 These pumps cause a gentle stirring or agitating of the oil in each pan, such oil being withdrawn from the upper exposed surface of the mass in each pan, and fed into the successive pan adjacent the bottom thereof at a point spaced a substantial distance from the upper exposed surface of the mass. In this manner a portion of the oil is kept in 120 continuous circulation, the same being withdrawn from the surface of the oil in the pan 125 130

and returned to the same adjacent the bottom thereof. In this form of apparatus, the oil is forced to travel upwardly through the pipes 14 and 16, from one lower pan to the successive upper pan. The steam heating coils 20 are operated to maintain the temperature in the shell 5 at the desired degree, which is preferably from 150° to 160° C., although this temperature may be widely varied. The hydrogen may now be supplied into the shell 5. A pressure of approximately 100 pounds to the square inch is preferably maintained within the shell during the operation of the process, but such pressure may be widely varied, as may be found advantageous. It is thus seen that the masses or lakes of oil having a substantial depth, with the finely divided catalytic agent mixed or suspended therein, is subjected to the action of the hydrogen, while the same is being gently stirred or agitated to thoroughly mix the saturated portion of the oil with the unsaturated portion, whereby the hydrogen will be readily absorbed by the oil having a large exposed area and will penetrate the depth of the masses of oil to be readily absorbed by the unsaturated portion thereof. In this manner the absorption of the hydrogen by the oil is accomplished more quickly and for a prolonged period. In the practice of the process in my form of apparatus shown in Fig. 2, the steps of the process are the same, except that the oil is made to circulate downwardly from one pan to the other, such oil being finally returned from the lowermost pan to the uppermost.

It is to be understood that the form of my invention, herewith shown and described is to be taken as a preferred example of the same and that various changes in the same may be resorted to without departing from the spirit of the invention or the scope of the subjoined claims.

Having described my invention, I claim:—

1. The process of hydrogenating oils, fats, fatty acids, etc., containing unsaturated constituents, which consists in exposing a large surface area of the material carrying in suspension a finely divided catalytic agent and having a substantial depth, to the action of hydrogen, while moving the material without violent agitation.

2. The process of hydrogenating oils, fats, fatty acids, etc., containing unsaturated fatty constituents, which consists in exposing a large surface area of the material carrying in suspension a finely divided catalytic agent and having a substantial depth, to the action of hydrogen, and withdrawing a portion of the material to cause the material to move without violent agitation.

3. The process of hydrogenating oils, fats,

fatty acids, etc., containing unsaturating fatty constituents, which consists in exposing a large surface area of the material carrying in suspension a finely divided catalytic agent and having a substantial depth, to the action of hydrogen, and withdrawing the saturated constituents from the exposed surface of the material.

4. The process of hydrogenating oils, fats, fatty acids, etc., containing unsaturated fatty constituents, which consists in exposing a large surface area of the material carrying in suspension a finely divided catalytic agent and having a substantial depth, to the action of hydrogen, in the presence of suitable heat and pressure, and circulating a portion of the material by withdrawing the same from the exposed surface thereof and introducing it into the material near the bottom thereof.

5. The process of hydrogenating oils, fats, fatty acids, etc., containing unsaturated fatty constituents, which consists in placing the material carrying in suspension a finely divided catalytic agent into open pans whereby a large surface area of the material is exposed and the material has a substantial depth, subjecting the large exposed surface area of material to the action of hydrogen in the presence of suitable heat and pressure, and withdrawing the material from one pan and supplying the same to another pan.

6. The process of hydrogenating fatty material containing unsaturated fatty constituents, which consists in exposing large surface areas of supported and relatively deep flowing bodies of the material carrying in suspension a finely divided catalytic agent, to the action of an atmosphere containing hydrogen.

7. The process of hydrogenating oils, fats, fatty acids, etc., containing unsaturated fatty constituents, which consists in subjecting a mass of the material having a depth substantially greater than a film to the action of an atmosphere of hydrogen under pressure and in the presence of heat and a finely divided catalytic agent, subjecting the mass to a gentle circulating movement without violent agitation, withdrawing the saturated constituents from the upper exposed surface of the material, and feeding the oil or the like containing more or less unsaturated fatty constituents into the lower portion of the mass at a point spaced a substantial distance from the upper exposed surface thereof.

In testimony whereof I affix my signature in presence of two witnesses.

JOHN CURTIS CHEVALIER HOEHN.
